Attorney

UNITED STATES PATENT OFFICE.

JOHN LEVANDOFSKY, OF BUCHTEL, OHIO.

LOCK NUT.

Application filed December 12, 1923. Serial No. 680,138.

To all whom it may concern:

Be it known that I, JOHN LEVANDOFSKY, a citizen of the United States, residing at Buchtel, in the county of Athens and State 5 of Ohio, have invented certain new and useful Improvements in Lock Nuts, of which the following is a specification.

My invention relates to bolt and lock nuts.

An important object of the invention is 10 to provide a device of the above mentioned character, which is automatically actuated to lock the nut against unscrewing movement upon the bolt, when the nut is screwed upon the bolt a suitable distance.

15 A further object of the invention is to provide a device of the above mentioned character, which is simple in construction, strong and durable.

Other objects and advantages of the invention will be apparent during the course 20 of the following description.

In the accompanying drawings forming a part of this specification, and in which like numerals are employed to designate like 25 parts throughout the same,

Figure 1 is a side elevation of a bolt and nut lock embodying my invention,

Figure 2 is a central longitudinal section taken on line 2—2 of Figure 1,

30 Figure 3 is an end elevation of the same,

Figure 4 is a fragmentary central longitudinal section, showing the locking element before it is tripped, and

35 Figure 5 is a perspective view of the key and pivot locking element.

In the drawings, wherein for the purpose of illustration is shown a preferred embodiment of my invention, the numeral 10 designates a bolt, having a screw threaded portion 40 11, engaged by a nut 12. The screw threaded portion 11 has a longitudinal slot 13, as shown.

The numeral 14 designates a carrier or key, mounted within the longitudinal slot 45 or groove 13, but not sufficiently wide or thick to extend to the exterior of this groove. The carrier or key 14 is provided at its rear end with a radial head or extension 15, projecting into an annular recess 16, formed in 50 the rear of the nut 12. The carrier or key 14 does not prevent the rotation of the nut 12 upon the bolt, and when the nut is rotated for screwing the same upon the bolt, the head 15, by its engagement with the nut 55 12 feeds the carrier 14 inwardly with the nut.

The numeral 17 designates a locking element as a whole, which is preferably L-shaped. This locking element embodies a head or base 18, mounted within an opening 60 or recess 19 in the carrier or key 14, and pivoted therein at 20. Secured to the head or base 19, and arranged at a right angle thereto is a finger 21, which is suitably stiff and resilient. The outer face of the nut 12 carries ratchet teeth 22.

In operation, the nut is applied to the free end of the bolt, and is screwed thereon, as clearly indicated in Figure 4. When the nut has traveled sufficiently inwardly upon the 70 bolt, the free end of the bolt contacts with the head or base 18 of the locking element, swinging it from the vertical to the horizontal position. This base now enters the recess 19 and is adapted to travel with the 75 carrier into the groove 13, as clearly shown in Figures 1 and 2. The finger 21 now assumes a vertical or radial position and will trip over the ratchet teeth 22, as the nut is screwed up, but will lock the nut against 80 unscrewing movement, in the selected adjusted position. It is thus seen that the screwing movement of the nut may be continued within a substantial range, and it will lock against unscrewing movement when the 85 selected position is reached.

It is to be understood that the form of my invention herewith shown and described, is to be taken as a preferred example of the same, and that various changes in the shape, 90 size, and arrangement of parts may be resorted to, without departing from the spirit of my invention, or the scope of the subjoined claims.

Having thus described my invention, I 95 claim:

1. A bolt having a screw threaded portion and a longitudinal groove therein, a nut engaging the screw threaded portion and having ratchet teeth, a carrier slidable within the groove and having a part engaging the nut, and a locking element movably mounted upon the carrier and adapted to be automatically shifted by engagement with the bolt into engagement with the ratchet teeth 100 105 of the nut.

2. A bolt having a screw threaded portion and a longitudinal groove therein, a nut engaging the screw threaded portion and having ratchet teeth, a carrier slidable within the groove and having a part engaging the nut to be shifted thereby, and a pivoted 110

locking element secured to the carrier, said locking element having a head to contact with the end of the bolt to be shifted thereby and an arm to have engagement with the ratchet teeth of the nut.

3. A bolt having a screw threaded portion and a longitudinal groove therein, a nut engaging the screw threaded portion and having a recess upon one side thereof, 10 a carrier slidable within the groove and hav-

ing a laterally extending head to engage within the recess, said carrier having a recess in its outer end, a locking element pivoted within the recess and including a base and a resilient arm at a right angle to the base, and ratchet teeth carried by the outer end of the nut. 15

In testimony whereof I affix my signature.

JOHN LEVANDOFSKY.
